UNITED STATES PATENT OFFICE.

HOWARD HOWIE, OF ROCKWOOD, TENNESSEE, ASSIGNOR TO ROANE IRON COMPANY, OF ROCKWOOD, TENNESSEE, A CORPORATION OF TENNESSEE.

BURNER.

Application filed December 10, 1923. Serial No. 679,840.

To all whom it may concern:

Be it known that I, HOWARD HOWIE, a citizen of the United States, residing at Rockwood, in the county of Roane and State 5 of Tennessee, have invented new and useful Improvements in Burners, of which the following is a specification.

The present invention relates to gaseous fuel burners, and has for its object the provision of a burner intended for use in connection with boilers, although it may be used on heating furnaces, and hot blast stoves, or for any other purpose where heat is required.

An object of the invention is to provide a 15 burner which will insure the thorough combustion of the gas, or gases, and the proper commingling of the gas and air.

A further object of the invention is to provide means for regulating the admission of air into the body of the burner, and to provide for the blending of both air under pressure and induced or aspirated air with the fuel gas.

The present invention relates to burners of 25 the general type disclosed in the patent to Bradshaw, No. 1,157,841, October 26, 1915, this invention being an improvement upon the structure disclosed in that patent.

In employing burners of this type, it has 30 been found desirable to provide air under pressure to commingle with the gases, and also to afford a plurality of separated jets for the gaseous fuel which will initially direct the fuel into the burner in separated streams, the burner being constructed to maintain the streams separated until they are about to be discharged from the burner.

Referring to the accompanying drawings, 35 wherein there is shown one embodiment of the invention,

Fig. 1 is a side elevational view.

Fig. 2 is a front elevational view.

Fig. 3 is a bottom plan.

Fig. 4 is a vertical section.

Fig. 5 is a vertical section on the line 45 5-5 of Fig. 4, looking in the direction of the arrows.

Fig. 6 is a sectional detail on the line 50 6-6 of Fig. 4, looking in the direction of the arrows.

Fig. 7 is a longitudinal sectional view of the main body portion of the casing taken on the line 7-7 of Fig. 8, and showing the burner provided with a removable tip.

Fig. 8 is a horizontal section on the line 55 8-8 of Fig. 7.

Referring to the drawings for a more detailed description, 10 indicates a casing having an open combustion end 11, the body section of which, shown more clearly in Figures 2 and 4, has a transversely extending obstruction 12. The obstruction, at the combustion end, as will be noted, is comparatively narrow, and flares rearwardly, having upper and lower surfaces 13, 14, which are 60 inclined in the direction of the top and bottom walls of the casing to provide passages 15, 16, which become constricted towards the rear end of the casing.

The obstruction may be cast integrally 70 with the casing, and, as indicated in Figure 4, is preferably hollow. It may, at times, be found desirable to provide the burner with a removable tip. A suitable construction is indicated in Figures 7 and 8; in these 75 figures the obstruction is formed with a substantially vertical front wall 19, and rods 17 secured in the rear wall 18 project from openings in the front wall into a removable burner tip 19' which may be constructed of 80 fire brick or other suitable refractory material. The tip 19' is formed as a transversely extending web of a casing extension 11', the tip portion 19' of the extension being reinforced by a vertical web 19'' shown 85 in cross section in Figure 8. By making the tip removable it may be taken from the burner for cleaning and for renewal when worn.

Referring more particularly to Figures 5 90 and 7, it will be noted that the obstruction has, in its upper and lower walls, a plurality of openings 20, communicating with the passages 15, 16, and through which air entering the obstruction may be admitted to the 95 passages. At the sides, the casing is provided with openings 21 through which air may enter the obstruction from a conduit 23 (Fig. 5), which, preferably, encircles the casing so as to direct air through the side 100 openings 21, and into the passages 15, 16. Additionally, the casing has a series of openings 24 in its top and bottom walls (Figure 5) through which air under pressure enters 105 the passages 15 and 16 directly from the conduit 23.

At its rear end the body portion of the casing has a pair of substantially parallel

transverse webs 26, 27, which are spaced by a substantially U-shaped web 28, having top and bottom walls 29 forming with the webs 26, 27, jets 30, through which gaseous fuel 5 may be directed into the constricted portions of the passages 15 and 16, and longitudinally of the casing toward the combustion end 11.

A hood 31 of sheet metal, or other suitable material, is fastened, as at 32, to the casing, and serves to direct the fuel through the jets 30. Any suitable regulating means for the gas (not shown) may be positioned in the conduit 32' communicating with the 15 hood.

It will be found desirable to permit the induction of air by the stream of gaseous fuel in addition to the air under pressure flowing through the conduit 23 into the casing. For this purpose, the body of the casing has, adjacent the rear end of the obstruction, a passage 35, which communicates with openings 37 in a closure plate 38 above the jets and between the conduits 23 and 32', so that the streams of gaseous fuel entering the passages at the constricted portions thereof, with a comparatively high velocity, serve to draw the air through the openings and into the passages.

At the bottom of the body portion of the casing, an induced air passage 36 is closed by plate 39 having a series of openings 40 therein, through which the induced air may pass. The openings in the plates 37 and 39 are controlled by sliding dampers 42 having openings 43 therein adapted to be moved into and out of registry with the openings in the plates. The top damper is maintained in selected position by means of a stud 41 extending through the dampers and secured in each plate. A compression spring 41' surrounding the stud serves to press an abutment 41'' against the damper, and hold the same in any position to which it is moved. A lever 45 may be provided for operating the bottom damper, the same being fulcrumed upon a pin 47, and having a forked end which engages a stud 46 upon the damper. Straps 46' (Fig. 3) secured 50 to the casing extend across the damper and hold the same in position, the damper having depending side ribs 43' engaging the straps.

It may be noted, at this point, that the 55 openings 20, in the obstruction, as well as the openings 24 in the top and bottom of the casing, all of which are for the air under pressure, are located so as to admit the air into the constricted portions of the passages, 60 assuring a commingling of the air and gases as promptly as possible after the admission of the gases into the burner, and thereby affording time for proper commingling of the same.

65 It will be observed that the amount of in-

duced air entering the burner may be nicely controlled. Under certain circumstances, it may be also desirable to regulate the supply of air under pressure, and, for this purpose, the bottom of the conduit 23 (Figures 4 70 and 5) is closed by a transversely extending plate 50, having a series of openings 51 therein, which are normally closed by means of a sliding damper 52, adapted to be retained in position by means of a pin 75 53 extending through a slot 54, and surrounded by a spring 55 which serves to maintain the damper in frictional engagement with the plate 50.

Obviously, the openings 52', in the damper, may be moved in and out of registry with the openings 51 in the plate 50, and when these openings are brought into registry, soot and dust which settle from the gas may be periodically removed to prevent obstruction of the gas opening.

From the foregoing, it will be apparent that both air under pressure and induced air, or either alone, may be mixed with the gaseous fuel, both being introduced into the 90 constricted portions of the passages 15, 16. At the points where the air and gases meet, the gas and air have considerable velocity, but as they approach the open combustion end of the casing, the velocity head decreases. The streams in the passages 15, 16, approaching to the tip of the obstruction, where they meet, commingle prior to combustion; by the separation of these streams until the air and gases in each stream are thoroughly commingled, and the subsequent blending of the separate streams, there is obtained a more intimate mixture of air and gas than is possible when the entire body of gas entering the burner is mixed with the air. The obstruction serves to divide the gas into separate portions, and also to divide the air so that after the separate portions are mixed, the two streams are combined at the combustion end of the casing.

It should be understood that numerous modifications may be made in the structure illustrated and described without departing from the scope of the invention.

I claim:

1. A gas burner comprising a casing, an obstruction extending transversely of said casing and having two surfaces which diverge from an open combustion end of the casing inwardly toward opposite walls forming narrowing passages between the obstruction and the walls of the casing, the casing having a series of air inlet openings adjacent the narrow portion of said passages, means for directing a forced air draft through said openings and into the passages, the casing being provided with additional air inlet openings for induced air adjacent the widest portion of said obstruction, means for regulating the size of said last mentioned 115 120 125 130

- openings, and fuel jets positioned rearwardly of said obstruction adapted to direct fuel through said passages.
2. A gas burner comprising a casing, having an open combustion end, an obstruction extending transversely of said casing and dividing the same throughout the width, said obstruction being relatively narrow at the combustion end of the casing and having upper and lower surfaces which diverge toward the opposite walls of the casing to form narrowing passages therethrough between the obstruction and the wall of the casing, the casing having air inlet openings adjacent the narrower portions of said passages, means for directing a forced air draft through said openings, the said casing having additional inlet openings for induced air adjacent the rear end of said obstruction and above and below the same, means for regulating the size of said last mentioned inlet openings, and fuel jets positioned rearwardly of said obstruction adapted to direct fuel through the passage in said casing.
3. A gas burner comprising a casing, having an open combustion end, an obstruction extending transversely of said casing and dividing the same into two compartments, said obstruction increasing in width from the outer combustion end where it is relatively narrow toward the rear of the casing to form passages on opposite sides of the obstruction which become constricted toward the rear end of the same, said casing having air inlet openings adjacent the rear end of said obstruction, means for directing a forced air draft through said openings, the casing being provided with a series of openings to admit induced air into the constricted portions of said passages, means for controlling said last mentioned inlet openings, and fuel jets positioned rearwardly from said obstruction adapted to direct fuel through the passages in said casing.
4. A gas burner comprising a casing, having an open combustion end, an obstruction extending transversely of said casing and dividing the same into two compartments, said obstruction increasing in width from the outer combustion end where it is relatively narrow toward the rear of the casing to form passages on opposite sides of the obstruction which become constricted toward the rear end of the same, said casing having air inlet openings adjacent the rear end of said obstruction, means for directing a forced air draft through said openings, the casing having additional inlet openings adapted to admit air into the ends of said obstruction at the sides of the casing, and the obstruction having adjacent its rear end openings to permit air from the interior thereof to pass into said passages, the casing being provided with a series of openings to admit induced air into the constricted portions of said passages, means for controlling said last mentioned inlet openings, and fuel jets positioned rearwardly of said obstruction adapted to direct fuel through the passages in said casing.
5. A gas burner comprising a casing having an open combustion end and a series of openings in its wall, a conduit for air under pressure communicating with the interior of the casing through said series of openings, an obstruction in said casing extending transversely of the same and forming two separated passages, the obstruction being relatively narrow at said combustion end of the casing and flaring toward the rear end thereof to narrow said passages, said series of openings admitting the air under pressure into said passages adjacent the rear end of said obstruction, and the casing having a series of openings for induced air adapted to direct the same into the constricted portions of said passages, means for regulating the sides of said last mentioned openings, and a fuel jet for each passage positioned at the rear end of the obstruction and adapted to direct fuel longitudinally of the passage.
6. A gas burner comprising a casing having an open combustion end and a series of openings in its wall, a conduit for air under pressure extending around said casing and communicating with the interior of the casing through said series of openings, an obstruction in said casing extending transversely of the same and forming two separated passages, the obstruction being relatively narrow at said combustion end of the casing and flaring toward the rear end thereof to narrow said passages, said series of openings admitting the air under pressure into said passages adjacent the rear end of said obstruction, and the casing having a series of openings for induced air adapted to direct the same into the constricted portions of said passages, means for regulating the size of said last mentioned openings, and a fuel jet for each passage positioned at the rear end of the obstruction and adapted to direct fuel longitudinally of the passage.
7. A gas burner comprising a casing having an open combustion end and a series of openings in its wall, a conduit for air under pressure extending around said casing and communicating with the interior of the casing through said series of openings, an obstruction in said casing extending transversely of the same and forming two separated passages located above and below said obstruction, the obstruction being relatively narrow at said combustion end of the casing and flaring toward the rear end thereof to narrow said passages, said series of openings admitting the air under pressure into said passages adjacent the rear end of said obstruction, and the casing having a series of openings for induced air adapted to direct fuel longitudinally of the passage.

rect the same into the constricted portions of said passages, means for regulating the size of said last mentioned openings, and a fuel jet for each passage positioned at the rear end of the obstruction and adapted to direct fuel longitudinally of the passage.

8. A gas burner comprising a casing having an open combustion end and a series of openings in its wall, a conduit for air under pressure communicating with the interior of the casing through said series of openings, an obstruction in said casing extending transversely of the same and forming two separated passages, the obstruction being relatively narrow at said combustion end of the casing and flaring toward the rear end thereof to narrow said passages, said series of openings admitting the air under pressure into said passages adjacent the rear end of said obstruction, and the casing having a series of openings for induced air adapted to direct the same into the constricted portions of said passages, means for regulating the size of said last mentioned openings, and a fuel jet for each passage positioned at the rear end of the obstruction and adapted to direct fuel longitudinally of the passage.

9. A gas burner comprising a casing having an open combustion end and a series of

openings in its wall, a conduit for air under pressure extending around said casing and communicating with the interior of the casing through said series of openings, an obstruction in said casing extending transversely of the same and forming two separated passages located above and below said obstruction, the obstruction being relatively narrow at said combustion end of the casing and flaring toward the rear end thereof to narrow said passages, said series of openings admitting the air under pressure into said passages adjacent the rear end of said obstruction and into said obstruction through the sides thereof, there being openings in the wall of the obstruction permitting forced air directed into the obstruction to pass into said passages, and the casing having a series of openings for induced air adapted to direct the same into the constricted portions of said passages, means for regulating the size of said last mentioned openings, and a fuel jet for each passage positioned at the rear end of the obstruction and adapted to direct fuel longitudinally of the passage.

In testimony whereof I have hereunto set my hand.

HOWARD HOWLE.
